Specification of Letters Patent.

Patented June 1, 1915.

Application filed May 27, 1912. Serial No. 629,870.

To all whom it may concern:

Be it known that I, CHARLES G. ASHLEY, a citizen of the United States of America, and a resident of Chicago, county of Cook, 5 and State of Illinois, have invented a new and useful Improvement in Printing-Telegraph Systems and Alphabets, of which the following is a specification.

My invention relates to automatic printing telegraph systems and pertains especially to systems of the class which employ a plurality of component printing elements or types, the complete legible characters being formed by impressions in proper relation 10 and sequence from a plurality of the component types representing the various component parts of the characters to be recorded.

My invention comprises a novel and extremely simple system of apparatus and circuits by means of which I am enabled to utilize for both apparatus operation and transmission purposes the currents and frequencies in common use for lighting and 15 power purposes and at the same time attain a high transmission speed as well as an extremely legible record. I accomplish these and other desiderata which will subsequently be disclosed herein, by employing a novel 20 type of motor which is operated by a primary current to impart lineal motion to the recording and transmitting tapes, while the imprinting currents are secondary and of 25 two intensities, their secondary nature making their respective instantaneous maximum 30 current values available for transmission purposes at intervals when the transmitting tape moving mechanism is substantially stationary, while the two intensities of the secondary 35 current allow of utilizing a sufficient number of component types to insure an extremely legible record. Further, by a design 40 of printing symbol and alphabet, I am enabled for any given frequency of current 45 to utilize an extremely short transmitting tape for a given message and to transmit this message at a maximum speed. I thus reduce the mechanism to a maximum of 50 simplicity which makes for low maintenance, ease of operation and small cost of manufacture.

Hitherto in the art, it has been the practice to employ as an isolated source of current for transmission purposes either bat-

teries or motor driven generators and the use of these has increased the cost of the instrument and its bulk and has further added to the cost of maintenance and difficulties of adjustment.

In the figures which accompany and form a part of this specification and in which like numerals designate corresponding parts throughout Figure 1 is a diagrammatic view partly in perspective of the transmitting and receiving apparatus with the conductors connecting them. Fig. 2 is an enlarged plan view of the printing types as they are arranged in the form of a monogram in the receiver. Fig. 3 is a plan view of the printing mechanism of the receiver. Fig. 4 is a diagrammatic view of the tape moving mechanism at the receiving station, together with an elevation of the printing mechanism. Fig. 5 shows a sectional transmitting tape perforated to transmit all of the Roman characters and Arabic numerals and shows further the appearance of the characters as imprinted on the recording tape.

The transmitter shown at the left in Fig. 1 comprises a transformer 23 the primary of which is connected through conductors 26 and 27 with any convenient commercial lighting or power circuit, while one terminal of the secondary is connected through conductor 24 with ground; a series of variant-voltage taps as 23', 23², 23³ and 23⁴ are taken from the secondary, a relatively high voltage tap 23² being connected to an insulated brush or plate 14, while a relatively low voltage tap 23⁴ is connected to the insulated brush or plate 15. A brush 12 bears upon and makes contact with plate 15 while a brush 13 bears upon and makes contact with both plates 15 and 14. Brush 12 is connected to line conductor 10 while brush 13 is connected to line conductor 11. A drum 16 which may be of metallic or non-metallic material, is provided with a median row of equally spaced projections 16' and is rigidly mounted upon a shaft 16² in close proximity with plates 14 and 15 and in such relation thereto that a transmitting tape provided with a median row of perforations engaging the projections 16' may be drawn by the rotation of drum 16 longitudinally between the brushes 12 and 15 and the platen formed by the plates 14 and 15. A

ratchet wheel 17 is rigidly attached to the shaft 16² and rotates therewith and with drum 16. A pair of pawls 18 and 19 are each pivoted at one extremity to the extremities of the bell crank 20 and are retained against the teeth of the ratchet wheel 17 by means of the springs 18' and 19' respectively. The armature 28 is rigidly attached to the bell crank 20 and the member 10 so formed is pivoted by means of the shaft 20' to one pole of the polarizing magnet 25. The armature 28 is free to swing about its pivot 20' between the pole faces of the electromagnets 21 and 22 which are mounted rigidly to the remaining pole of the magnet 25. The windings of the electromagnets 21 and 22 are connected in series and to the commercial supply source through conductors 26 and 27. The magnets 21 and 22 are 15 so wound and connected that when energized, unlike magnetic poles are induced on their pole faces, that is their magnetic poles are in rotation. An alternating primary current of a definite frequency when energizing magnets 21 and 22 therefore causes armature 28 to vibrate in unison therewith, thus rocking the bell crank 20 about pivot 20' and through pawls 18 and 19, ratchet wheel 17 and shaft 16², imparting rotary 20 motion to drum 16.

Ratchet wheel 17 is provided with twice as many teeth as there are projections on the drum 16, and the ratchet wheel is so placed in angular relation with the drum 16 that 35 the radial face of every second tooth is always in the same radial plane as that occupied by the radial axis of a projection as 16'. Thus given a 60 cycle operating source of current, armature 28 will make one vibration per cycle and rotate the drum 16 through an angular distance equal to that defined by the distance between any three successive teeth on the ratchet wheel 17 or one-half the distance between any two projections as 16'. While the drum 16 is being thus rotated, there is being placed on plate 15 through the tap 23⁴ of the secondary of transformer 23 a positive and negative potential of a definite intensity 40 and simultaneously there is being placed on plate 14 through secondary tap 23² a positive and negative potential of a relatively higher intensity. As brush 12 bears upon plate 15 and is connected to line conductor 10, there is being placed successively upon that conductor positive and negative potential of a definite intensity, while as brush 13 bears upon both plates 15 and 14, it is possible through a predetermined spacing of perforations in a transmitting tape to 45 allow brush 13 to make contact with either plate 15 or 14 and thereby to place selectively upon line conductors 10 or 11 positive or negative potentials of variant intensities.

The contact line of the brushes 12 and 13 with the platen formed by plates 14 and 15 is maintained a distance from the axis of rotation of drum 16 which is a multiple of the unit of motion of the transmitting tape. 70 This unit being defined as that distance through which the tape is moved while drum 16 is rotated through one half the angular distance between any two consecutive teeth on the ratchet wheel 17 or that is while armature 28 is making one complete movement in one direction. Thus, as the secondary current lags substantially 90° behind the primary current the dividing line between any two consecutive tape intervals 75 falls under the contact line of the brushes with the platen at that instant when the necessary current of the transformer 23 is at a maximum instantaneous value. For while armature 28 is making a complete movement in one direction thus moving drum 16 through one angular unit, the secondary current of that particular potential is building up to a maximum value which is reached at substantially the instant when the primary current is zero or that is, when the armature 28 and drum 16 are substantially stationary and hence by a correct transverse and longitudinal spacing of perforations in a transmitting tape, it is possible to selectively place over either line conductor to ground a positive or negative impulse of current of a definite intensity and upon one line to ground a positive and negative impulse of current of variant intensity. 80 The correct longitudinal spacing of the perforations in the tape insures that these current impulses will be available for transmission at instants of the maximum value 85 of their respective potentials. 90

Referring now especially to Figs. 1, 3 and 4, the receiving apparatus comprises a U shaped polarizing magnet 30, one leg of which extends a distance beyond the other and is provided with a series of aligned openings as 4² Fig. 4. Five operating solenoids 1, 2, 3, 4 and 5 are positioned within the U shaped magnet with their central openings in register with the respective openings as 4² in magnet 30 and are rigidly attached thereto to maintain such register. The shorter leg of magnet 30 extends slightly inwardly beyond the outline of the central openings of each of the solenoids. A plate of magnetic material 32 is attached to the longer leg of magnet 30 and serves to support the pole piece 31 which extends inwardly beyond the outline of the central openings of all of the solenoids and is maintained at a definite distance from the face of the shorter leg of magnet 30 to provide a definite air gap for the polarizing magnet 30. 100

One extremity of each of a series of bell crank shaped armatures 1', 2', 3', 4' and 5' passes through their respective apertures in 105

magnet 30 and the hollow central portions of their respective operating solenoids 1, 2, 3, 4 and 5 and extend beyond the pole faces of magnet 30. A pivot pin 33' passes 5 through all of the armatures and is pivoted in two journal blocks as 33 which are in turn rigidly attached to the under surface of magnet 30. A printing type, as 1°, 2°, 3°, 4° and 5°, is borne as an integral part there- 10 of upon each extremity of the armatures 1', 2', 3', 4' and 5' respectively which lie without the operating helix and these extended portions of the armatures are bent to bring their respective type faces into such relation to each other as to form the printing monogram shown in Fig. 3, or as shown greatly enlarged in Fig. 2. The solenoids 3 and 4 controlling armatures 3' and 4' and consequently printing the types 3° and 4° 15 20 are connected in series, with their magnetic poles when energized in rotation, and to the line conductor 10 and ground. The solenoids controlling armatures 2', 5' and 1' and consequently printing types 2°, 5° and 1°, 25 are connected in series with the magnetic poles of solenoids 2 and 5 in rotation and the magnetic poles of solenoids 5 and 1 in parallel and the group so formed is connected to line conductor 11 and ground. Thus an im- 30 pulse of current over line conductor 10, through solenoids 3 and 4 to ground induces unlike poles upon the extremities thereof while an impulse of current over line conductor 11 through solenoids 2, 5 and 1 to ground induces unlike poles upon the extremities of solenoids 2 and 5 and like poles 35 on the extremities of solenoids 5 and 1. The solenoids 3, 4, 2 and 5 are wound to operate their respective armatures when energized by one predetermined intensity of current, while solenoid 1 is wound to operate its armature only when energized by a current intensity which is substantially 2, 3 or more times that necessary to operate armatures 3', 4', 2' or 5'. 40 45

An anvil 34 is placed adjacent to all of the printing types and is adjustable in its distance therefrom. A receiving tape 34' rests on the surface of the anvil 34 and is drawn longitudinally between the anvil and the printing types by means of the roller 35 and idler 50. A strip of impression paper 34° is maintained between the printing types and the receiving tape 34' and allows of recording the impression of the types on the recording tape.

A ratchet wheel 36 which is the exact counterpart of the ratchet wheel 17 of the transmitter is rigidly attached to the shaft 50 of the roller 35 and rotates therewith and with the roller 35. The mechanism for imparting rotary motion to roller 35 is in all respects similar to that used in the transmitter and comprises the pawls 37 and 38 which are each pivoted at one extremity to the ex-

tremities of the bell crank 39 and are retained in position against the teeth of the ratchet wheel 36 by means of the springs 37' and 38' respectively. An armature 48 is rigidly attached to the bell crank 39 and 70 the member thus formed is pivoted by means of the pin 39' to one extremity of the polarizing magnet 40. The armature 48 is free to move about its pivot 39' between the pole faces of a pair of electromagnets 41 and 42 which are rigidly attached to the remaining extremity of the polarizing magnet 40. The electromagnets 41 and 42 are connected in series with their magnetic poles in rotation and are connected to the leads 46 and 47 of any commercial lighting or power source of alternating current at the receiving station. A transformer 43 is connected to the leads 46 and 47 as at the transmitting station, the secondary of the transformer being connected to the transmitting apparatus at the receiving station which is in all respects similar to that shown in Fig. 1. Thus assuming that the leads 46 and 47 are connected to a 60 cycle supply current, 80 the armature 48 will vibrate at the same rate as the armature 28 at the transmitting station and through the pawls 37 and 38, ratchet wheel 36', roller 35 and idler 50, will draw the receiving tape 34' longitudinally 90 under the printing type faces at the same or a proportionally lineal rate as that at which the transmitting tape is drawn through the transmitter at the transmitting station, dependent upon the relative diameters of the 95 drums 16 and 35. 100

The operation of my device is as follows: Assuming that the primary of the transformer 23 at the transmitting station is connected with a 60 cycle source 105 of current and that magnets 21 and 22 are likewise connected to this source of current and assuming further that the magnets 41 and 42 at the receiving station are connected with a similar source of current 110 at the receiving station, then if a perforated transmitting tape be provided with a central row of registry perforations and be placed on drum 16 so that these perforations invaginate the projections 16', the tape may 115 be drawn between the brushes 12 and 13 and the plates 14 and 15 at a uniform rate as hitherto explained. Now if a recording tape be placed between the roller 35 and idler 50, it will be drawn under the type faces 1° 2° 3° 4° and 5° at the same or a proportionally lineal rate as that of the transmitting tape as has hitherto been explained. The lineal rate at which the transmitting and receiving tapes move is such that a unit of length of each tape passes under the contact line of brushes 12 and 13 and under the printing types respectively, while the respective primary currents are making one half cycle. At the transmitting station while the pri- 120 125 130

mary current is making one half cycle and the transmitting tape is moving longitudinally over one unit of length under brushes 12 and 13, the secondary currents are building up to a maximum instantaneous value of the same potential as the primary potential at that instant and are impressed on the plates 14 and 15. This maximum instantaneous value of the secondary is reached 10 when the transmitting tape has moved under the contact line of the brushes 12 and 13 with plates 14 and 15 one complete tape interval. If now a perforation be placed in the transmitting tape and be so spaced laterally that it allows contact to be made 15 between brush 12 and plate 15 at the instant when the tape has moved over one tape unit and is at rest, an impulse of current of maximum instantaneous value which I will 20 assume occurs at that instant in a current cycle when its potential is positive will be sent from the secondary of induction coil 23 through tap 23⁴, plate 15, brush 12, line conductor 10, through operating solenoids 3 25 and 4 to ground and thence back to the secondary of transformer 23. Now, as the polarizing magnet 30 of the receiver normally maintains all of the armatures 1', 2', 3', 4' and 5' with their upper extremities 30 against the pole face of its shorter leg, the pen faces 1°, 2°, 3°, 4° and 5° are normally restrained from contact with the impression paper 34². Hence a positive impulse of current through solenoids 3 and 4 will, as they 35 are wound to have opposite poles when energized, reverse the polarity of one of their inclosed armatures as 4' from that polarity created therein by the polarizing magnet 30 and it will be repelled by the hitherto at- 40 tracting pole face of the polarizing magnet and urged by the influence of its operating solenoid and the opposite pole face 31 to move toward pole face 31, thus causing its printing type 4° to strike the impression 45 paper and record an impression of pen face 4° upon the receiving tape.

The energization of solenoid 3 with a current impulse of positive potential causes its normal polarity to be accentuated and it 50 is, therefore, more strongly held against the polarizing magnet out of contact with the impression paper. Simultaneously through a perforation in the transmitting tape laterally spaced to allow of contact being made 55 between brush 12 and plate 15, after the tape has been moved by the drum 16 through the next succeeding tape unit, a negative impulse of current of maximum instantaneous value may be sent through the secondary 60 tap 23⁴, plate 15, brush 12, line conductor 10, solenoids 3 and 4, and ground to operate armature 3' to imprint its type face 3° while type face 4° is more strongly held out of contact with the impression paper. In a

like manner, perforations may be spaced 65 laterally in the tape to allow contact to be made between brush 13 and plate 15, and may be further so spaced longitudinally as to transmit to solenoids 2, 5 and 1 positive or negative impulses of current from sec- 70 ondary tap 23⁴, to operate respectively printing types 5° and 2°. However, as solenoid 1 is adjusted to require substan- 75 tially three times the current necessary to operate armatures 2' and 5', it does not op- 80 erate to imprint printing type 1° when ener- 85 gized with current from secondary tap 23⁴ which operates armatures 3', 4', 2' and 5'. If, however, a perforation in the trans- 90 mitting tape be so laterally spaced as to allow 95 of contact being made between brush 13 and plate 14 and longitudinally spaced so as to permit a positive impulse of current, or the same polarity as that which operates armature 5' of substantially three times the 95 voltage of the current used to operate armatures 2', 5', 3' and 4', will be sent from the secondary tap 23² to plate 14, brush 13, line conductor 11, solenoids 2, 5 and 1 to ground and thence through ground to secondary of 100 transformer 23 which operates both armatures 5' and 1' to simultaneously imprint printing types 5° and 1°. At the receiving 105 station, the tape 34² is being drawn longitudinally under the printing types at a 110 lineal rate which is equal, or proportional to, the lineal speed of the transmitting tape in order that by the operating of the trans- 115 mittor the impressions of the types may be recorded in proper relation to preceding 120 imprints to build up legible characters.

Referring now to Fig. 2, in which I have shown a plan view of the printing types, as they appear in the receiver, or the figure may be looked upon as an enlarged record 105 of the imprints of all of the types were they simultaneously imprinted upon a stationary receiving surface, type faces 1°, 2° and 3° are each in width equal to the width of a complete normal character such as "A". A 110 normal character is divided into two arbitrary units of width, and printing types 2° and 3° are separated from types 1°, 5° and 4° by one of these arbitrary units. Printing 115 type 1° abuts at one extremity with one extremity of type with 5° while types 4° and 5° abut at one extremity each and are aligned longitudinally. The drum 36 is of such relative diameter with drum 16 that while the transmitting tape is moving one 120 longitudinal unit, the receiving tape is moving, or has moved, dependent upon the phase relation between the operating current at the transmitting station and the operating current at the receiving station, 125 a distance which is proportional to the distance moved by the transmitting tape and is further equal to the arbitrary unit of

width of the pen faces 2° and 3° or one half the width of a complete normal character.

Referring now to Fig. 5, which illustrates a section of transmitting tape perforated with all of the perforations necessary to transmit the characters of the alphabet and numerals from 0 to 9, and the outline of the characters as they appear on the receiving tape, the longitudinal line (3-4) is an arbitrarily chosen line of contact between brush 12 and plate 15. The longitudinal line 56 is a median line, along which the registry perforations, which invaginate the projection 16' on drum 16 are placed. The longitudinal line (2-5) is an arbitrarily chosen line of contact between brush 13 and plate 15 while the longitudinal line (5 and 1) is a similarly chosen line of contact between brush 13 and plate 14. The transverse lines 1+, 2-, 3+ and 4- are spaced a distance apart, which is defined by the angular distance through which the drum 16 is moved by a complete movement in one direction of armature 28' caused by a one half cycle of the operating current and, as hitherto explained, while the secondary current is changing from a maximum of one potential to a maximum of the opposite potential. I have arbitrarily chosen a ratchet wheel with twice as many teeth as there are projections on the drum 16 and as the drum is rotated through the angular distance of one half the distance between any two successive teeth in the ratchet wheel for every half cycle of operating current, there are between any two successive registry perforations in the transmitting tape four tape intervals or instants when the instantaneous maximum value of the secondary current may be utilized for transmission purposes, hence, while the tape is moving under the contact line of the brushes 12 and 13 with the plates 14 and 15, a distance of four of these tape intervals, there will be impressed on the plates 14 and 15, two cycles of secondary current, which will reach their respective maximum values at instant when the dividing line between any two tape intervals is under the contact line of the brushes 12 and 13 with the plates 14 and 15. A perforation spaced along the line (3-4) will allow of contact being made between brush 12 and plate 15 to send positive and negative impulses through solenoids 3 and 4 while a perforation spaced along the line (2-5) will allow of contact being made between brush 13 and plate 15 to send positive and negative impulses through solenoids 2 and 5. A perforation spaced along line (5 and 1) will allow of contact being made between brush 13 and plate 14 to send positive and negative impulses of augmented intensity through solenoids 2, 5 and 1 to operate armatures 5' and 1' simultaneously. The

longitudinal spacing of the perforations 65 along any of the longitudinal lines determines the polarity of the impulses as hitherto explained.

The method of building up legible characters is as follows: Assuming the transmitter and receiver in operation, as hitherto explained, then the transmitting tape, Fig. 5, is being drawn longitudinally from right to left between the brushes 12 and 13, and plates 14 and 15, and the receiving tape 34' 70 is being drawn from right to left under the type faces, as viewed in Fig. 2. And assuming further that the secondary current reaches a maximum positive value at that instant when the rotation of the drum 16 has 75 brought a registry perforation in the transmitting tape on the contact line of brushes 12 and 13 with plates 14 and 15. Then a pair of perforations along the transverse line 1+, one on the longitudinal line (3-4) 80 and the other longitudinal line (5 and 1), will allow of contact being made simultaneously between brush 12 and plate 15, and brush 13 and plate 14 to send a positive impulse of current of a relatively low intensity 85 and maximum instantaneous value over line conductor 10 through solenoids 3 and 4 to ground to operate armature 4', and a positive impulse of current of a relatively high intensity and maximum instantaneous value 90 over line conductor 11 through solenoids 2, 5 and 1 to ground to operate simultaneously armatures 5' and 1', resulting in simultaneously imprinting on the recording tape 34' 95 through the medium of the impression paper 100 34² an impression of type faces 4°, 5° and 1°; after the transmitting tape has moved two tape intervals during which time the receiving tape has moved two units of width of a complete normal character or the width of 105 a normal character, a pair of perforations in the transmitting tape along the transverse line 3+ one spaced longitudinally along line (3-4) and the other along the line (2-5), allow of contact being made 110 simultaneously between brush 12 and plate 15, and brush 13 and plate 15 to simultaneously send over line conductors 10 and 11 positive impulses of relatively low intensity 115 and maximum instantaneous value through solenoids 3, 4, 2, 5 and 1 to operate armatures 4' and 5' to imprint simultaneously on the receiving tape 34' impressions of type faces 4° and 5°. These impressions will, as the receiving tape has moved the width of a 120 complete normal character since the last impressions recorded thereon, fall with the upper extremity of the impression from type face 4° joining the free extremity of the impression of type face 1°. After the transmitting tape has moved one more interval 125 and the receiving tape has moved again one unit of width of a complete normal char-

acter, a perforation in the transmitting tape on the line 4— and longitudinally spaced on the line (2—5) allow of contact being made between brush 13 and plate 15 to send over line conductor 11 through solenoids 2, 5 and 1 a negative impulse of current of relatively low intensity and of maximum instantaneous value to operate armature 2' to imprint type face 2°. This impression, as the 10 receiving tape has moved since the last series of impressions a distance of one tape interval falls with its two extremities abutting the previous impressions of type faces 4° and 5° to form the character "A." In a 15 similar manner, all of the characters necessary to transmit intelligence in any language using Roman characters may be recorded on a receiving tape.

It will be noticed from the foregoing that 20 with my improved system, the maximum printing possibilities of an operating current of a definite frequency is realized to reduce the length of the transmitting tape to a minimum; that by such reduction I attain, for any given frequency of current, a 25 maximum transmission speed; and that through the elimination of bulky and unwieldy batteries and motor generators, I have greatly simplified the apparatus and 30 circuits and reduced the cost of manufacture and installation; and have, at the same time, through this reduction in the number of operating parts produced an instrument of positive operation and one on which the cost 35 of maintenance is very low. It will be further observed that as the transmitting tape passes through the transmitter at a comparatively high rate of speed and as the perforations are of small diameter the length 40 of the operating impulse, while of sufficient duration to insure proper operation of the printing types is, in reality, only momentary, thus the necessity for synchronism between the movement of the transmitter drum 45 and the receiver drum is eliminated for should the two operating currents be at a maximum variation with each other, that is in phase quadrature, and the receiving drum be in motion when the type faces strike the 50 impression paper, the interval during which the type face is in contact with the impression paper is of such extremely short duration that the impression recorded on the receiving tape will not be blurred objectionably by the tape dragging under the type faces. It should be further noted that as 55 the transmitter drum is moved through the angular distance defined as half the distance between the radial faces of any two successive teeth on the ratchet wheel 17, for each movement in one direction of the armature 28, the drum and ratchet wheel may be manually spun on their axis and allowed to come to rest with the pawls engaging the

teeth of the ratchet wheel without, in any 65 way, changing the relation of the potential of the instantaneous maximum value of the secondary current to the angular position of the drum 16.

While I have disclosed but one embodiment 70 of my device, it is to be clearly understood that I may make numerous changes in the details thereof without departing from the spirit or narrowing the scope of my invention. 75

Having thus described my invention, what I claim as new and desire to secure by the United States Letters Patent is as follows:

1. In a printing telegraph system, a source 80 of primary current, means for utilizing said current to effect translatory motion, means for deriving a secondary current from said primary current, a plurality of printing types, operating magnets associated therewith, and means for utilizing said translatory motion jointly with said secondary current to selectively impress on said operating magnets, current impulses of variant polarity.

2. In a printing telegraph system, a source 90 of primary current, means for inductively deriving a secondary current from said primary current, said secondary current being displaced in its phase relation with said primary current, means for utilizing said primary current to effect translatory motion, a 95 plurality of printing devices, operating magnets therefor, and means for utilizing the maximum instantaneous value of said secondary currents at instants of cessation of said translatory motion, to impress upon selected groups of said operating magnets current impulses of variant polarity. 100

3. In a printing telegraph system, a source 105 of primary current, a transmitting tape, means for utilizing said current to impart lineal motion to said tape, means for deriving a secondary current from said primary current, a plurality of printing types, operating magnets associated therewith, and 110 means for utilizing the lineal motion of said tape jointly with said secondary current to impress on said operating magnets, current impulses of variant polarity.

4. In a printing telegraph system, a primary source of alternating current, means 115 for deriving a secondary source of current from said primary source, means for utilizing said primary source of current to effect translatory motion, means for utilizing said secondary source of current for transmission 120 purposes, a plurality of printing types, operating magnets associated with said printing types and means for utilizing said translatory motion jointly with said secondary 125 current to selectively impress on said operating magnets current impulses of variant polarity.

5. In a printing telegraph system, a primary source of current, means for deriving a secondary source of current from said primary source, said secondary source being displaced in its phase relation with said primary current, a transmitting tape, means for utilizing said primary current to impart lineal motion to said tape, a plurality of printing elements, operating magnets associated therewith, and means for utilizing the maximum instantaneous value of said secondary current at instants of cessation of the lineal motion of said tape to impress upon said operating magnets current impulses of variant polarity.

6. In a printing telegraph system, a source of alternating current, a transformer the primary of which is connected to said source, a ratchet motor connected to said source, a transmitting tape, means for utilizing said motor to impart lineal motion to said tape, a secondary current derived through the medium of said transformer from said alternating current, a plurality of printing types, operating magnets therefor, and means for utilizing the motion of said tape and said secondary currents jointly to impress upon such operating magnets current impulses of variant polarity.

30 7. In a printing telegraph system, a primary source of current, means for deriving a secondary source of current from said primary source, a transmitting tape, means for utilizing said primary source of current to impart longitudinal motion to said tape, a plurality of printing elements, operating electro-magnets associated with said printing elements, and means for utilizing the longitudinal motion of said tape jointly with 35 said secondary currents, to selectively impress upon certain groups of said operating magnets current impulses of variant polarity and definite intensity and to impress upon other groups of said electro-magnets 40 current impulses of definite polarity and variant intensity.

8. In a printing telegraph system, a primary current, a second current displaced in its phase relation thereto, a transmitting 50 tape, means for utilizing said primary current to impart lineal motion to said tape, a plurality of printing elements operating magnets associated therewith and means for utilizing the maximum instantaneous value 55 of said other current at instants of cessation of the lineal motion of said tape to impress upon certain groups of said operating magnets current impulses of variant polarity and definite intensity and to impress 60 upon other groups of said operating magnets current impulses of definite polarity and variant intensity.

9. In a printing telegraph system, a source of alternating current, a transformer

the primary of which is connected to said source, a ratchet motor connected to said source, a transmitting tape, means for utilizing said motor to impart lineal motion to said tape, a secondary current derived through the medium of said transformer 75 from said primary current and displaced in its phase relation thereto, a plurality of the printing types, operating magnets therefor, and means for utilizing the maximum instantaneous value of said secondary currents 70 at instants of the cessation of the motion of said tape to impress upon said operating magnets current impulses of variant polarity and intensity.

10. In a printing telegraph system, a source of alternating current, a transformer the primary of which is connected to said source, a ratchet motor connected to said source, a transmitting tape, means for utilizing said motor to impart lineal motion to 80 said tape, a secondary current derived through the medium of said transformer from said primary source and displaced in its phase relation thereto, a plurality of printing types, a polarizing magnet associated with all of said types, an operating solenoid associated with each of said types, and means for utilizing the maximum instantaneous value of said secondary current 85 at instants of cessation of motion of said transmitting tape to impress upon certain groups of said operating solenoids current impulses of variant polarity and definite intensity and to impress upon other groups of 90 said operating solenoids current impulses of variant intensity and definite polarity.

11. In a printing telegraph system, a transmission line, a transmission tape, a first source of alternating potentials for moving said tape intermittently, means for deriving 95 a secondary source of alternating potential inductively from said first source for impressing transmission currents on said line and means whereby said tape is moved between the maxima of potentials of said second source.

12. In a printing telegraph system, a transmission line, a transmission tape, an impulse motor for driving said tape, a series of motor driving impulses, a series of intermittent potentials having successive maxima with intervals therebetween and adapted to be applied to said line through the action of said tape, and means for maintaining such a phase relation between said motor driving 105 impulse and said intermittent potentials as to allow said motor driving impulse to operate said motor between successive maxima of said intermittent potentials.

13. In a printing telegraph system, a line, 115 a first alternating potential, a perforated tape, a motor driven by said first alternating potential and driving said tape and means

for deriving a second alternating potential from said first alternating potential, said second alternating potential being governed in its application to said line by said tape.

- 5 14. In a printing telegraph system, a transmission line, a plurality of printing types, operating electro magnets associated therewith and connected to said line, alternating potentials from a first source for impressing currents upon said line and said magnets, a perforated transmission tape controlling the application of said alternating potentials to said line and said magnets, alternating potentials from a second source 10 for moving said tape between the maxima of said potentials, and means for deriving said first source of potentials from said second source of potentials.

15. In a printing telegraph system, a line, 20 a plurality of printing types, operating electromagnets associated therewith and connected to said line, a series of intermittent potentials having successive maxima with intervals between, a perforated tape governing the application of said potentials to said line and said magnets, an impulse motor for driving said perforated tape, and a series of 25 motor driving impulses acting in the intervals between the successive maxima of the 30 said series for application to the line and means for inductively deriving said series of intermittent potentials from said series of motor driving impulses.

16. In a printing telegraph system, a line, 35 a plurality of printing types, operating electromagnets associated therewith and connected to said line, a first alternating potential, a perforated tape governing the application of said alternating potential to said 40 line and said magnets, motor for driving said tape, a second alternating potential for driving said motor and means for inductively deriving said first alternating potential from said second alternating potential.

- 45 17. In a printing telegraph system, a source of primary current, a transmitting tape, means for utilizing current from said source to shift said tape, means for deriving a secondary current inductively from said 50 source of primary current, a plurality of printing types, operating magnets associated therewith and means for utilizing said tape when shifted and jointly with current from said secondary source to selectively 55 impress on said operating magnets, current impulses of variant polarities.

- 60 18. In a printing telegraph system, a source of primary current, means for inductively deriving a source of secondary current from said primary current, said secondary current being displaced in its phase relation to said primary current, a transmitting tape, means for utilizing current from said primary source to shift said tape

intermittently, a plurality of printing devices and operating magnets therefor and means for utilizing the maximum values of currents from said secondary source at instants of cessation to said tape shifting to impress upon selected groups of said operating magnets current impulses of variant polarities.

65 19. In a printing telegraph system, a source of primary current, a secondary source of current, a transmitting tape, 70 means for utilizing current from said primary source to shift said tape intermittently, a plurality of printing types and operating magnets associated therewith, a means for utilizing the shift of said tape 75 by said primary current and jointly with said secondary current to selectively impress on said operating magnets current impulses of variant polarities.

80 20. In a printing telegraph system, a primary source of current, a secondary source of current, means for deriving said currents from a single source of energy and displacing their phase relations to each other, a transmitting tape, means for utilizing one of said currents to impart lineal motion to said tape, a plurality of printing elements, operating magnets associated therewith, and means for utilizing the maximum instantaneous value of the other of 90 said currents at units of cessation of the lineal motion of said tape to impress upon said operating magnets current impulses of variant polarities.

85 21. In a printing telegraph system, a primary source of current, a secondary source of current, means for deriving said currents from a single source of energy and for displacing their phase relations to each other, a transmitting tape, means for utilizing one 100 of said currents to impart lineal motion to said tape, a plurality of printing elements, operating magnets associated therewith and means for utilizing the maximum instantaneous value of the other of 105 said currents at units of cessation of the lineal motion of said tape to impress operating currents upon said magnets.

110 22. In a printing telegraph system, a source of alternating current, a transformer, 115 the primary of which is connected to said source, a ratchet motor connected to said source, a transmitting tape, means for utilizing the said motor to impart lineal motion to said tape, secondary currents derived through the medium of said transformer from said alternating current, a plurality of printing types, operating magnets therefor, and means for utilizing the motion of said tape and said secondary currents jointly to impress upon said operating magnets current impulses of variant polarity.

23. A source of primary current, means for deriving a secondary current from the primary current, a series of type operated by the impulses of the secondary current, 5 and devices operated by the primary current for controlling the impulses of the secondary current.

24. A source of primary current, means for deriving a secondary current from the 10 primary current, a series of type, a corresponding series of magnets for operating the type, connections through which the impulses of the secondary current operate said magnets, and devices operated by the primary current for selectively controlling the 15 impulses of the secondary current.

25. A source of primary current, means for producing a secondary current, a series of type, a magnet for each type, connections through which impulses of the sec- 20

ondary current flow through two magnets in series to operate them individually by impulses of opposite polarity, and devices operated by the primary current for selectively controlling the impulses of the sec- 35

ondary current. 26. A series of type, a magnet for each type, means for sending successive impulses to operate said magnets, an intermittently movable impulse selector, and means for 30 causing the impulses to alternate with the movements of the selector.

Signed by me at Toronto, county of York, and Province of Ontario, in the presence of two witnesses.

CHARLES G. ASHLEY.
